C. P. KIMBALL, OF PORTLAND, MAINE.

Letters Patent No. 99,207, dated January 25, 1870

IMPROVEMENT IN SLEIGHS.

The Schedule referred to in these Letters Patent and making part of the same.

To all whom it may concern:

Be it known that I, C. P. KIMBALL, of Portland, in the county of Cumberland, and State of Maine, have invented a new and useful Improvement in Sleighs; and I hereby declare the following to be a full, clear, and exact description of the same, reference being had to the accompanying drawings, forming part of this specification, in which is seen a side elevation of a portion of a sleigh, with my improvement thereon.

The purpose of my improvement is to provide a device, convenient and easy of access, for cleansing the bottoms of the covering of the feet, before entering the sleigh, so as to do away with the liability to carry snow, moisture, and dirt into the sleigh, or on the robes or rugs, &c. Whatever of snow, &c., that may adhere to the boots of a person entering a sleigh, is usually removed by knocking the feet against the posts or the runners of the vehicle.

I propose to attach, at some point between the runner and the rail of a sleigh, and at a convenient place near to where persons usually step into a sleigh, a piece of wood or metal, or a combination of the two, with such an edge that before entering the vehicle, the bottoms of the feet can be drawn over the same, in order to remove all adhering substances, and to enable the person getting in to do so with clean feet.

The drawings show a convenient and secure method of thus attaching the device, *a* being the scraper, *b*, a metal brace, running diagonally down from the post

c to the runner *d*, and the other end of the scraper being bolted into the post *e*. Thus the device is easily used by any one, either standing on the ground or in the sleigh.

The scraper may rise from the runner by two uprights, and other similar methods might be employed.

As seen in the drawing, the brace *b* and the scraper are of one piece of metal.

I do not, of course, claim a foot-scraper, however constructed, irrespective of its combination or association.

I do not here claim, broadly, a scraper, when attached to vehicles. I limit this application to an improvement in sleighs.

The brace *b*, by itself, is not new.

The scraper *a*, being in a line, or nearly in a line, with the posts and runner, is not liable to catch to anything, and so be broken off.

What I claim as my invention, and desire to secure by Letters Patent, is—

1. The improved brace *b*, that is, when made together with the scraper *a*, and to support, or aid in supporting the same, as herein set forth.

2. The described combination of the brace *b*, having, as a part of it, the scraper *a*, with the two posts *c* and *e*, and with the runner *d*, as set forth.

C. P. KIMBALL.
